US0D1038126S

(12) **United States Design Patent** (10) **Patent No.:** **US D1,038,126 S**
(45) **Date of Patent:** **** Aug. 6, 2024**

(54) **ACCESS CONTROL DEVICE**

(71) Applicant: **Axis AB**, Lund (SE)

(72) Inventors: **Jonas Sjögren**, Lund (SE); **Mariano Vozzi**, Lund (SE); **Sebastian Engwall**, Lund (SE); **Örjan Nilsson**, Lund (SE); **Henrik Tengqvist**, Lund (SE)

(73) Assignee: **AXIS AB**, Lund (SE)

(**) Term: **15 Years**

(21) Appl. No.: **29/831,435**

(22) Filed: **Mar. 21, 2022**

(51) LOC (14) Cl. **14-02**

(52) U.S. Cl.

USPC **D14/387**; D14/383

CLAIM

The ornamental design for an access control device, as shown and described.

DESCRIPTION

FIG. 1 is a top, front, right perspective view of an access control device in accordance with our design;

FIG. 2 is a top, rear, left perspective view thereof;

FIG. 3 is a front elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a rear elevational view thereof.

The broken lines represent portions of the access control device in which the design is embodied that form no part of the claimed design.

1 Claim, 6 Drawing Sheets
